United States Patent Office

Des. 232,660
Patented Sept. 3, 1974

232,660

WHEEL ALIGNMENT HEAD

John D. McKenney, South Laguna, Calif., assignor to
Royal Industries, Inc., Osseo, Minn.

Filed Sept. 20, 1972, Ser. No. 290,472

Term of patent 14 years

Int. Cl. D10—05

U.S. Cl. D52—6 E

FIG. 1

FIG. 2

FIG. 3

FIG. 4

FIG. 5

FIG. 6

FIG. 1 is a top plan view of a wheel alignment head showing my new design.

FIG. 2 is a front elevational view thereof.

FIG. 3 is a bottom view thereof.

FIG. 4 is a left end elevational view thereof.

FIG. 5 is a right end elevational view thereof.

FIG. 6 is a rear elevational view thereof.

I claim:

The ornamental design for a wheel alignment head, as shown.
